US00D458863S

(12) **United States Design Patent**
Harding et al.

(10) **Patent No.:** **US D458,863 S**
(b4) **Date of Patent:** **** Jun. 18, 2002**

(54) **COMPACT ELECTRIC METER**

- (75) Inventors: **Stewart J. Harding; Markus F. Hirschbold; I. Ross Macfarlane**, all of Victoria; **Werner Reinhard Simbeck**, Mill Bay, all of (CA)
- (73) Assignee: **Power Measurement, Ltd.**, Saanichton (CA)
- (**) Term: **14 Years**
- (21) Appl. No.: **29/142,153**
- (22) Filed: **May 18, 2001**

Related U.S. Application Data

- (63) Continuation of application No. 09/791,419, filed on Feb. 23, 2001, which is a continuation of application No. 09/791,421, filed on Feb. 23, 2001.

(57) **CLAIM**

The ornamental design for a compact electric meter, as shown and described.

DESCRIPTION

FIG. 1 is a front perspective view of our new, original and ornamental design for a compact electric meter, according to a first embodiment;

FIG. 2 is a left side view of the meter of FIG. 1;

FIG. 3 is a back perspective view of the meter of FIG. 1;

FIG. 4 is a right side view of the meter of FIG. 1;

FIG. 5 is a front view of the meter of FIG. 1;

FIG. 6 is a bottom view of the meter of FIG. 1;

FIG. 7 is a back view of the meter of FIG. 1;

FIG. 8 is a top view of the meter of FIG. 1;

FIG. 9 is a front perspective view of our new, original and ornamental design for a compact electric meter, according to a second embodiment;

FIG. 10 is a left side view of the meter of FIG. 9;

FIG. 11 is a back perspective view of the meter of FIG. 9;

FIG. 12 is a right side view of the meter of FIG. 9;

FIG. 13 is a top view of the meter of FIG. 9;

FIG. 14 is a front view of the meter of FIG. 9;

FIG. 15 is a back view of the meter of FIG. 9;

FIG. 16 is a bottom view of the meter of FIG. 9;

FIG. 17 is a back perspective view of our new, original and ornamental design for a compact electric meter, according to a third embodiment;

FIG. 18 is a top view of the meter of FIG. 17;

FIG. 19 is a front view of the meter of FIG. 17;

FIG. 20 is a back view of the meter of FIG. 17;

FIG. 21 is a bottom view of the meter of FIG. 17;

FIG. 22 is a left side view of the meter of FIG. 17; and,

FIG. 23 is a right side view of the meter of FIG. 17.

The broken lines in the Figures are for illustrative purposes only and form no part of the claimed design.
